(57) **CLAIM**

The ornamental design for a seed treatment reservoir, as shown and described.

DESCRIPTION

FIG. 1 is a front, top, and right side perspective view of a seed treatment reservoir, as shown and described;

FIG. 2 is a rear, bottom, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings showing portions of the seed treatment reservoir are included for the purpose of illustrating environmental structure and form no part of the claimed design.

1 Claim, 8 Drawing Sheets
